UNITED STATES PATENT OFFICE.

WILLIAM G. DODGE, OF NEWBURYPORT, MASSACHUSETTS, ASSIGNOR TO UNITED SHANK & FINDINGS COMPANY, OF BOSTON, MASSACHUSETTS, A CORPORATION OF MASSACHUSETTS.

TURN SHOE AND SHANK STIFFENER THEREFOR.

Application filed May 4, 1921. Serial No. 466,682.

This invention relates to improvements in turn shoes and shank stiffeners therefor. A turn shoe is customarily provided with a shank stiffener, frequently termed a turn shank, consisting of a more or less flexible stiffener member, commonly called a filler piece, of leather or leatherboard which is shaped to fit within the heel and shank portions of the shoe, and a metallic reinforcing strip which is attached to the lower side of the filler piece. At its heel end the stiffener member or filler piece is commonly secured to the shoe by the heel-attaching nails. The shank portion of the filler piece, however, is either left entirely unattached or it is secured in place merely by glue or by a small tack in such a manner that this portion of the filler piece usually becomes detached after the shoe has been worn a short time. When unsecured to the sole the shank portion of the filler piece is capable of moving longitudinally relatively to the sole when the shoe is flexed, as when the wearer is walking. As a result in most turn shoes the shank stiffener cannot be relied upon properly to support and stiffen the arch or shank.

In view of the foregoing, one object of the present invention is to provide a turn shoe of improved construction which will insure the desired adequate and permanent stiffening of the shank or arch of the shoe.

To the attainment of this object the invention, considered in one aspect, as herein exemplified, consists in a turn shoe having a shank stiffener comprising a filler piece extending over the heel and shank portions of the sole and a reinforcing strip for the filler piece, means for rigidly securing both ends of the reinforcing strip to the filler piece, means for rigidly securing the heel end of the filler piece to the sole, and fastening means extending through the sole of the shoe and through both the filler piece and the reinforcing strip forwardly of the heel of the shoe rigidly to secure together the shank stiffener and the sole. As illustrated, the fastening means is a rivet which is clinched inside of the shoe and securely locks both the filler piece and the reinforcing strip to the shank portion of the sole so that the latter is adequately and permanently supported or stiffened.

In another aspect the invention resides in the provision of an improved shank piece or shank stiffener unit for a turn shoe compris-

ing a stiffener member or filler piece shaped to conform substantially to the outline of the heel and shank portions only of the inside of a turn shoe and provided with a perforation in its shank portion for the reception of a rivet for securing the shank stiffener unit to the sole, a longitudinally arched metallic strip for reinforcing the shank portion of the stiffener member and having a perforation for the reception of said rivet, and means at each end portion of the reinforcing strip for securing the latter to the stiffener member or filler piece with said perforations in registration.

The invention will be explained with reference to the accompanying drawings, in which—

Fig. 1 is a diagrammatic plan view of a metal strip from which a plurality of reinforcing strip blanks have been cut;

Fig. 2 is a plan view of a reinforcing strip blank;

Fig. 3 is an end view of the blank;

Fig. 4 is a view, partly in section and partly in elevation, illustrating the shaping of the blank;

Fig. 5 is a side elevational view, partly in section, of the improved shank stiffener showing the leather stiffener member or filler piece with a metallic reinforcing strip made fast thereto;

Fig. 6 is a longitudinal section through a turn shoe in which the improved shank stiffener is incorporated; and

Fig. 7 is a plan view of a metal strip from which has been cut a plurality of reinforcing strip blanks of modified form.

In Figure 1 of these drawings is shown a metallic strip 1, which is cut at intervals therethrough to form individual reinforcing strip blanks 2. Each blank terminates at its ends in prongs 3 and is punched or perforated at 4, preferably in the blank cutting operation. Each blank is then formed for example, between dies as shown in Fig. 4, the prongs 3 being bent or struck up at the desired angle and the central portion of the strip being curved to conform to the longitudinal curvature of the shoe shank and having a central longitudinal stiffening rib 5 formed therein. In Fig. 5 there is shown at 6 a piece of leather, leatherboard or other suitable material, which is shaped to conform to the heel and shank portions only of the inside

of the sole of a turn shoe and which has a thin skived forward end 7. This piece 6 constitutes a stiffener member or filler piece of the type ordinarily reinforced by a metallic reinforcing strip to form what is commonly known as a "turn shank" or "shank stiffener for turn shoes."

The metal reinforcing strip which is made from the blank 2 is made fast between the 10 ends of the filler piece 6 by means of the prongs 3, which are driven and clinched therein. The prongs 3 serve to maintain the strip 2 and the filler piece 6 in assembled relation with the perforations 8 and 9 in registration so as to facilitate the insertion of a rivet or other fastener through them after they have been placed in a shoe. The filler piece 6 is then perforated at 8 in alinement with the hole 4. Thus a shank stiffener unit 20 is produced which is ready for incorporation in a shoe. Next, the stiffener unit, consisting of the filler piece 6, and the metal reinforcing strip, is placed in position in a turn shoe, as shown in Fig. 6, and the sole of the shoe is 25 perforated at 9 in alinement with the holes 4 and 8 and substantially centrally of its shank portion. A rivet 10 is passed through the registering holes in the sole, the reinforcing strip, and the filler piece, and the rivet is 30 clinched at 11 within the shoe. The forward end portion of the filler piece may be made fast to the sole by any suitable securing means and the rear end of the filler piece may also be made fast to the sole by means such as 35 the heel attaching nails 12. The above described method is claimed in a divisional application Serial No. 186,739, filed April 26, 1927.

The modified form of reinforcing strip blank shown in Fig. 7 is designed for the purpose of decreasing the waste in the blanking or cutting out of the metal reinforcing strip. In this case prongs 3', corresponding to the prongs 3, are made at one end of the 45 metal blank, and prongs 3^a are formed at the other end of this blank, the prongs 3^a of one blank nesting within the prongs 3' of the adjacent blank. By this means the waste from the cutting of the prongs is much reduced and the number of blanks which may be cut from a long strip of stock somewhat increased. In other respects the construction is the same as before described.

In Fig. 6 there is shown a turn shoe of the 55 sort produced by the practice of the above-described method. The illustrated shoe has incorporated therein a shank stiffener unit consisting of the stiffener member or filler piece 6 and a metallic reinforcing strip. The 60 reinforcing strip is firmly secured by the prongs 3 to the stiffener member 6. The stiffener member or filler piece 6 is shaped to conform substantially to the outline of the heel and shank portions of the inside of the 65 shoe. The perforation 8 in the stiffener mem-

ber 6 is in registration or alinement with the perforation 4 in the reinforcing strip, both said perforations being formed preliminarily to the assembly of the stiffener unit with the sole of the shoe. In the sole of the shoe 70 shown in Fig. 6 the perforation 9 is in registration with the alined perforations 4 and 8 in the component parts of the stiffener unit and the stiffener unit is secured to the sole by the rivet 10 which extends through the perforations 9, 4 and 8. The heel attaching nails 12 75 secure the rear portion of the filler piece 6 to the shoe while the forward extremity of the filler piece may be left unsecured or may be secured in any suitable manner, as may be 80 desired.

By the provision of a turn shoe having incorporated therein a turn shank stiffener as herein described, a firmly supported and adequately stiffened shank or arch construction 85 is secured. Both the filler piece and the metal reinforcing strip are rigidly secured to the shank of the sole, a result which has not heretofore been accomplished so far as the inventor is aware. The assembling and securing together of the parts of the shank stiffener and also the incorporating of the stiffener in a shoe may be conveniently and expeditiously practised. This will be apparent when it is realized that the fastener-receiving perforation 8 in the filler piece is initially formed in alinement with the perforation 4 in the reinforcing strip and also that the perforation 9 in the sole of the shoe is initially formed in alinement with the alined perforations 4 and 8 in the reinforcing strip and filler piece. Consequently when the filler piece and the reinforcing strip are being assembled, and later when the stiffener unit composed of these two parts is being assembled with the sole of the shoe, it is unnecessary to waste time by bringing into registration fastener-receiving perforations originally made out of registering relation in the various parts. Furthermore, the arrangement is such that the herein described fastening means permanently and rigidly secures the stiffener unit and the sole in assembled relation to preserve the arch at the shank of the shoe.

Having thus described my invention, what I claim as new and desire to secure by Letters Patent of the United States is:—

1. A turn shoe having a shank stiffener comprising a stiffener member and a reinforcing strip fixed at its ends to said stiffener member, a single fastener extending through the shank portion of the sole of the shoe and through both the stiffener member and the reinforcing strip and rigidly securing said stiffener member and strip to the sole, and other means for securing the stiffener member only to the sole at a point spaced from said fastener.

2. A turn shoe having a shank stiffener

comprising a filler piece extending over the heel and shank portions of the sole and a reinforcing strip for the filler piece, means for rigidly securing both ends of the reinforcing strip to the filler piece, means for rigidly securing the heel end of the filler piece to the sole and fastening means extending through the sole of the shoe and through both the 5 filler piece and the reinforcing strip forwardly of the heel of the shoe rigidly to secure together the shank stiffener and the sole.

3. A shank stiffener for turn shoes comprising a filler piece shaped to conform to the interior outline of the shank and heel portions of the bottom of a shoe and having a fastener-receiving perforation preliminarily formed in its shank portion, a metallic reinforcing strip having a preliminarily formed fastener-receiving perforation extending 10 therethrough at a point intermediate between its end portions and arranged with its perforation registering with the perforation in the filler piece, and means unassociated with either of said perforations and securing 15 said filler piece and said reinforcing strip together in the relation specified.

4. A shank stiffener unit for a turn shoe comprising a stiffener member shaped to conform substantially to the outline of the heel 20 and shank portions only of the inside of a turn shoe and having a perforation in its shank portion to receive a rivet for securing 25

the shank stiffener unit to the sole, a longitudinally arched metallic strip for reinforcing the shank portion of said stiffener member and having a perforation for the reception of said rivet, and means at each end portion of said reinforcing strip securing 30 said strip to said stiffener member with said perforations in registration.

5. A turn shoe comprising, in combination, a sole, a shank stiffener member shaped to conform substantially to the outline of the inside of the shoe and having a rivet-receiving perforation in its shank portion, means for rigidly securing the heel portion of said stiffener member to the sole of the shoe, a metallic reinforcing strip for said stiffener member having a rivet-receiving aperture 45 therein, means at the opposite end portions of said reinforcing strip for securing the latter to said stiffener member with said apertures in registration, and a rivet extending through the sole substantially at the middle 50 of its shank portion and through the registering apertures in the stiffener member and the reinforcing strip rigidly to secure the stiffener member and the reinforcing strip 55 to the sole.

In testimony whereof I have affixed my signature.

WILLIAM G. DODGE.
